UNITED STATES PATENT OFFICE.

HENRY J. APPLETON, OF DETROIT, MICHIGAN.

ANNUNCIATOR.

1,335,215.

Specification of Letters Patent. Patented Mar. 30, 1920.

Application filed September 15, 1919. Serial No. 323,691.

To all whom it may concern:

Be it known that I, HENRY J. APPLETON, a citizen of the United States, residing at Detroit, in the county of Wayne and State 5 of Michigan, have invented certain new and useful Improvements in Annunciators, of which the following is a specification.

This invention relates to street car annunciators, and has for its object a street 10 car annunciator provided with a novel form of operating apparatus to give a differential peripheral speed to the rolls. It also has novel features in driving the rollers which will more fully appear when the detailed 15 description is understood.

In the drawings,—

Figure 1 is a plan view of the driving apparatus for the rolls.

Fig. 2 is a vertical section through the 20 casing showing the driving apparatus and rolls in elevation.

Fig. 3 is a side elevation of the rolls and driving apparatus and a vertical section of the housing or case.

Fig. 4 is a detail showing one of the gears 25 for securing a differential peripheral driving speed.

Fig. 5 is a side elevation of the driving pinion shown in Fig. 4.

Fig. 6 is an elevation showing the trip switch and trip loop, used in connection 30 with the trolley.

Fig. 7 is an elevation of the same parts but taken at a 90 degree angle from that 35 of Fig. 6.

Fig. 8 is a section taken on the line 8—8 of Fig. 6.

Fig. 9 is a section taken on the line 9—9 of Fig. 6, showing the spring for keeping 40 the trip switch open.

Fig. 10 is a right hand view of the members 100 of Fig. 6.

Fig. 11 is a diagrammatic view of the apparatus.

Fig. 12 designates the housing which is of roughly T-shape in cross section, as shown in Fig. 3, with observation windows b and c in the front and back of the annunciator. The brackets d and e are at their bottoms 45 fastened to the sides of the casing and at their tops are fastened to the top of the casing. An angle bracket f runs across the top of the casing and serves to secure the sides to the top of the casing. An angle 50 brace g fastens the two side pieces of the casing (Fig. 2) together to allow the upper

part of the casing to be offset for the purpose of forming a chamber for the driving mechanism. The upper roller h is journaled in the supporting brackets e and d, 60 as is also the lower roller i. The sign-bearing ribbon j is drawn off from the upper roll over the guide rollers k and onto the lower roll, or vice versa. The lower roll i is driven by the belt l (Fig. 3) that runs 65 over the sheaves m and onto the sprocket n which is on the end of a shaft o fastened to the driving cone p (Fig. 2). This driving cone p (Fig. 4) is provided with a spiral 70 thread q notched to form teeth r, which engage with the teeth of the driving pinion s. The sides of the driving pinion are beveled 75 to engage between the opposed faces of the two outside threads of any group of three, while the teeth engage the teeth of the intermediate thread of any group of three. Hence, inasmuch as the thread is a spiral, 80 this pinion is caused to travel longitudinally upon the squared driving shaft t, while it also rotates the cone. Obviously 85 as it travels to the right in Fig. 4, it would increase the rotating speed of the cone, while traveling to the left of Fig. 4 would decrease the speed. There is also a cone p and a driving pinion s for the upper roll h. 90 This is mounted to the other side of the upper roll h and is provided with a sprocket u (Fig. 3) which drives the upper roll through the belt v and the sprocket w. Obviously when one driving pinion s is 95 traveling in one direction on its shaft, the other pinion will be traveling in the opposite direction, and whereas the peripheral speed of one roll increases due to the winding of the ribbon thereupon, the peripheral speed of the other roll decreases due to the unwinding of the ribbon therefrom. This different direction of travel of the two pinions s can be accomplished by having a right 100 and left hand thread on the two cones. The two squared shafts t are driven by the sprocket wheels x and y which in turn drive the beveled gear z that meshes with the spur gear 1 on the end of the squared shaft t. These two sprockets x and y are driven by 105 the chain 2 that runs over the large sprocket wheel 3 on the end of the shaft 4 (Fig. 2) which is provided with a pair of ratchet wheels 5 and 6 at its opposite end. These ratchet wheels have teeth that face in opposite directions. The ratchet wheel 5 is 110 driven by the rack bar 7 (Fig. 3) and the

ratchet wheel 6 is driven by the lower rack bar 8. These two rack bars are jointed to the rods 9 and 10 respectively, which run through the guide brackets 11 and 12. The 5 upper rod 9 is bolted to a yoke bar 14 (Fig. 1) which is connected with a pair of solenoid plungers 16 that are sucked outwardly by the solenoids 15 against the resistance of the retracting spring 17 that engages with 10 the outer end of the pin 19. When the spring retracts the plungers and the racks the inclined outer ends 20 (Fig. 3) ride up on the pins 21, which disengages the rack teeth from the ratchet teeth. This enables 15 either rack to drive its ratchet so that a reversal of the driving mechanism can take place at any time. The lower rack 8 is connected with a yoke 23 that has the plungers 24 at its ends, and these plungers are sucked 20 out by the operation of the pair of solenoids 25. The spring 26 in connection with the pin 27 serves to retract the solenoid plungers 24 and the rack 8. The flat spring 28 (Fig. 3) tends to keep the teeth of the upper 25 rack 7 in engagement with the ratchet teeth. The spring 29 serves to keep the teeth of the lower rack 8 in engagement with the ratchet teeth. The ratchet wheels are kept locked when the sign-bearing ribbon is not being 30 shifted by means of the pin clutch 30 (Figs. 1 and 2) having pins 31 adapted to engage in the perforations 32 (Fig. 3) of the ratchet wheels. This clutch is released by the solenoid 33.

35 Turning to Figs. 6 to 10 inclusive, the trip switch which releases the clutch and furnishes the power to operate the driving solenoids, will be understood. 34 is the trolley pole; 35 the trolley wheel; 36 the trolley line; 37 the cross wire that supports the trolley line. The trip wire or loop 38 is supported from the cross wire 37 by means of the arm 39. The ends of this trip wire 38 are provided with cradles 40 that hook 40 under the trolley wire 36 and serve both to support this wire 36 and keep the trip wire or loop 38 from rocking. The trip switch comprises a pair of arms 41, each carrying a trip contact wheel 42. One trip 45 arm is expected to operate in travel one way on the track and the other trip arm to operate in travel in the opposite direction. It will be seen from Fig. 7 that the outer trip contact wheel 42 does not engage the trip wire 38. When traveling in the opposite direction the outer trip contact wheel 42 would engage another trip wire 39 properly located for this purpose. Each of these trip arms 41 is provided with a spring electrode 43 adapted to make contact with the spring electrode 44. When the trip arm 41 is tipped back by reason of the trip contact wheel 42 striking the trip wire 38, this establishes a circuit, which can be 50 traced in the diagrammatic view in Fig. 65

11. This serves to energize the proper pair of solenoids and at the same time release the clutch. The travel of the solenoids and the accompanying rack bar turns the proper ratchet wheel a given distance, which in turn rotates the two driving cones and through them the rolls. When the trip switch is released the spring 50 returns the trip arm and the solenoid spring returns the rack bar and the clutch is disengaged by 75 its spring.

The finger switches 45 and 46, shown in Fig. 2 and diagrammatically in Fig. 11, are for the purpose of moving the upper or lower rack bar in precisely the same way 80 as the trip switch does. This may be necessary if for any reason the ribbon gets out of step with the trip switches along the way.

What I claim is:

1. In an annunciator, the combination of 85 a pair of rolls, a sign bearing ribbon adapted to wind on one of the rolls and off the other roll, and compensating means comprising a pair of cones placed at opposite sides of the periphery of one of the rolls, 90 a driving connection from one of the cones to one of the rolls, a second driving connection from the other cone to the other roll, and an automatically-shiftable driver for each cone, the drivers for the cones being 95 shifted longitudinally of the cones in opposite directions to increase the speed of one roll and simultaneously decrease the speed of the other roll.

2. In an annunciator, the combination of 100 a pair of rolls, a sign-bearing ribbon traveling over the rolls, and means for driving the rolls and including two ratchet wheels having oppositely-facing teeth and which rotate together, two rack bars one for each 105 set of teeth normally held out of contact therewith, and separate solenoids that may be selectively energized to bring one of the rack bars into engagement with one of the ratchet wheels and rotate the ratchet wheel 110 in either direction by moving one or the other of the rack bars.

3. In an annunciator, the combination of 115 a pair of rolls, a sign-bearing ribbon passing over the rolls, and means for driving the rolls including a pair of ratchet wheels fastened together and having oppositely-directed teeth, two rack bars one for each set of teeth normally held out of contact with the teeth, separate solenoids for moving 120 each rack bar, a clutch for locking the two ratchet wheels, and means for disengaging the clutch and simultaneously and selectively energizing either of the solenoids.

4. In an annunciator, the combination of 125 a pair of rolls, a sign-bearing ribbon passing over the rolls, and means for driving the rolls in either direction including a pair of ratchet wheels which rotate together but

having oppositely-directed teeth, a pair of rack bars one for each ratchet wheel, separate solenoids for actuating each rack bar, a pin clutch for locking the ratchet wheels, 5 and electrical connections for simultaneously disengaging the pin clutch and selectively operating either solenoid to drive the ratchet wheels in either direction.

5. In an annunciator, the combination of a 10 pair of rolls, a sign-bearing ribbon passing over the rolls, and means for driving the same including a pair of ratchet wheels hav-

ing oppositely-directed teeth, a pair of racks one for each set of teeth, separate solenoids 15 separately energizable for moving the rack bars to turn the ratchet wheels, means for retracting the rack bars, pins, and an inclined surface on each rack bar for engaging a pin when the rack bar is retracted to lift the rack bar out of engagement with the 20 teeth of the ratchet.

In testimony whereof I affix my signature.

HENRY J. APPLETON.
